(57) **CLAIM**

The ornamental design for an eye drop bottle with positioning device, as shown and described.

DESCRIPTION

FIG. 1 is a perspective side view of an eye drop bottle with positioning device showing my new design;

FIG. 2 is a side view thereof; the opposite side view being a mirror image;

FIG. 3 is a top view thereof;

FIG. 4 is a bottom view thereof; and,

FIG. 5 is a cross-sectional side view thereof.

In FIG. 2, the broken lines showing the environmental structure for purposes of illustrating the eye drop bottle with positioning device in a condition of use. The broken lines and the structure they depict form no part of the claimed design.
